(57) **CLAIM**

The ornamental design for a bracelet, as shown and described.

DESCRIPTION

FIG. 1 is a top perspective view of an embodiment of a bracelet showing my new design.

FIG. 2 is a bottom perspective view thereof.

FIG. 3 is a rear elevational view thereof.

FIG. 4 is a front elevational view thereof.

FIG. 5 is a right side elevational view thereof; and,

FIG. 6 is a left side elevational view thereof.

The broken lines showing the other bracelet features are for the purpose of illustrating environmental structure and form no part of the claimed design.
